UNITED STATES PATENT OFFICE.

ALEXANDER EBEN CHISHOLM, OF SEATTLE, WASHINGTON.

DIVING APPARATUS.

1,367,587.

Specification of Letters Patent.

Patented Feb. 8, 1921.

Application filed October 2, 1919. Serial No. 327,875.

To all whom it may concern:

Be it known that I, ALEXANDER E. CHISHOLM, a citizen of the United States, residing at Seattle, in the county of King and State of Washington, have invented new and useful Improvements in Diving Apparatus, of which the following is a specification.

My invention relates to improvements in diving apparatus, particularly well adapted for use in deep sea diving, but not necessarily restricted to this use.

An important object of the invention is to provide apparatus of the above mentioned character, which is adapted to be suspended and lowered from a ship or barge, in such a manner that the apparatus will not partake of improper turning movement, and will be shifted in accordance with the movements of the ship or barge.

A further object of the invention is to provide simple and efficient holding or grappling means, easily operated from the interior of the casing of the apparatus.

A further object of the invention is to provide an apparatus of the above mentioned character, which is very strong, and is therefore adapted to withstand high pressure, without liability of collapsing.

Other objects and advantages of the invention will be apparent during the course of the following description.

In the accompanying drawings forming a part of this specification and in which like numerals are employed to designate like parts throughout the same,

Figure 1 is a side elevation of apparatus embodying my invention.

Fig. 2 is a plan view of the same.

Fig. 3 is a central longitudinal section through the apparatus.

Fig. 4 is a detail section through the holding or grappling means.

Fig. 5 is an enlarged side elevation of a spring washer,

Fig. 6 is a detail section taken on line 6—6 of Fig. 4,

Fig. 7 is an enlarged longitudinal section through a slightly different form of yielding means for the holding device.

In the drawings, wherein for the purpose of illustration is shown a preferred embodiment of my invention, the numeral 10 designates a preferably cylindrical casing, which is suitably thick to withstand high pressure without collapsing. The casing 10 may be

formed of iron, steel, or the like, and it may be corrugated, if desired. The casing 10 has a substantial length, and its lower end is closed by a base or bottom 11 preferably in the form of a heavy plate, provided with a flange 12, projecting into the casing, and secured thereto by bolts or rivets. The outer portion or edge of the bottom 12 is in the form of an annular flange 14, extending radially beyond the casing 10, for a substantial distance, as shown.

A reinforcing ring 15 is arranged upon the upper end of the casing 10, and extends radially beyond the same, for a substantial distance. The ring 15 carries a depending flange 16, projecting into the casing 10, and secured thereto by bolts or rivets 17. It is obvious that the ring 15 and the bottom 11 serve to reinforce and stiffen the ends of the casing 10, and reinforcing rings 18 may be arranged within the casing 10, near its central portion, and rigidly secured thereto. These rings may be in any suitable shape in cross section.

The numeral 19 designates a top or cover for the casing, preferably in the form of a conical plate-like structure as shown in the drawing, adapted to engage upon the ring 15, and having an inner flange 20, to fit 85 therein. The top or cover 19 is hinged to the ring 15, at 21. This cover is provided near its periphery with radial slots 22, receiving swinging clamping bolts 23, operating through slots 24 in the ring 15, and 90 pivotally connected therewith, beneath the same, as shown at 25. It is obvious that when the nuts 26 of the bolts 23 are suitably unscrewed, these bolts may be swung downwardly to the inactive position and the cover 95 19 swung upwardly to the open position.

The suspending means for the apparatus preferably comprises a pair of diametrically oppositely arranged flexible elements 27, which may be cables or the like. The lower 100 ends of this pair of cables are attached to the flange 14, as shown, while the cables pass through apertures 28, in the ring 15. These cables extend upwardly and are wound upon a drum or other hoisting mechanism carried 105 by the ship or barge, for suspending the apparatus, or raising and lowering it, or shifting the same with the movement of the ship or barge. The arrangement of the cables is important inasmuch as it prevents the casing 110 turning upon its longitudinal axis.

The numeral 29 designates a preferably

conical operating housing, increasing in diameter rearwardly, and bolted, at 30, to the casing 10, and surrounding an opening 31 in this casing.

5 At its forward or outer end, the housing 29 is provided with a flange 30', and central opening 31'. A gasket ring 32, is bolted to the flange 30, as shown at 33, and a packing ring 34, is arranged between these elements, 10 for effecting a water tight joint. The gasket ring 33 has a central opening 35, in registration with the opening 31.

The numeral 36 designates a flexible sleeve, preferably formed of rubber. This 15 sleeve has an inner enlarged or conical portion 37, the outer edge of which is clamped to the gasket ring 32, by a ring 38, and bolts 39, as shown.

The flexible sleeve 36 receives a guide 20 sleeve 40, having stuffing boxes 41, at the ends thereof. The flexible sleeve 36 has its outer end clamped to the guide sleeve 40 by a clamping ring 42.

The numeral 43 designates yielding supporting means, surrounding the guide sleeve 40, within the conical portion 37 of the flexible sleeve 36, and contacting with the gasket ring 32. This yielding means embodies a plurality of split spring washers 30 44, as clearly shown in Fig. 5.

As shown in Fig. 7, the yielding supporting means is in the form of a coil spring 45, which is conical, and decreases in diameter outwardly. This coil spring is arranged 35 within a flexible sleeve 35', similar to the sleeve 36, but having a slightly different shape. The other parts of the apparatus or associated elements remain the same.

The numeral 46 designates the holding or 40 grappling apparatus as a whole. This apparatus embodies an outer tube 47, slidable within the guide sleeve 40 and stuffing boxes 41, so that it may be shifted longitudinally and turned upon its longitudinal axis, if desired. A rod 48 is slidable within the outer tube 47 and also within stuffing boxes 49, carried by the ends of this outer tube. At its outer end, the rod 48 is provided with a laterally extending jaw 50, preferably circular in cross section, and having serrations 51, upon its inner side. This jaw is adapted to be shifted toward and away or sidewise from a stationary jaw 52, preferably semi-circular in cross section, and having its 55 edges serrated, at 53. The jaw 52 is carried by a shank 54, secured to a clamp 55, rigidly attached to the outer tube 47. At its inner end, the rod 48 is bent laterally to form a hand grip 55', arranged near a co- 60 acting stationary hand grip 57, carried by a clamp 58, which is rigidly mounted upon the tube 47.

The numeral 59, designates a sight opening housing, bolted to the casing 10, and 65 having its opening covered by a section of

glass 60, suitably thick, and held in place by suitable means. A sight opening is arranged near and above the housing 29 and enables the operator to observe the object being grasped by the holding device.

70

I preferably provide a propeller 61, near the lower end of the casing, and this propeller is driven by a motor 62, within the casing 10. This motor may receive current from cables extending from the ship or 75 barge. I also contemplate the use of a telephone line between the apparatus and the ship.

In the use of the apparatus, the operator, 80 enters the casing 10, by way of the open cover 19, which is subsequently closed and locked in the closed position. The casing 10 is sufficiently large to hold a proper amount of air for the use of the operator for a suitable time. The casing 10 is now 85 lowered into the water by the unwinding of the cables 27. When the casing is moved into proximity to the object to be collected, the operator may telephone to the ship or barge, and by suitable movement of the 90 ship the casing may be brought suitably near the object, or the casing may be shifted by a propeller 61, so that it may be grasped between the jaws 50 and 52. These 95 jaws are operated by the movement of the tube 47 and rod 48, from the interior of the casing, as explained. The operator may then telephone to the ship and the casing will be raised, the jaws carrying with them the desired object.

100

It is to be understood that the form of my invention herewith shown and described is to be taken as a preferred example of the same, and that various changes in the shape, size, and arrangement of parts may 105 be resorted to without departing from the spirit of my invention, or the scope of the subjoined claims.

Having thus described my invention, I 110 claim:—

110

1. In diving apparatus of the character described, a hollow cylindrical casing; means for permanently closing the lower end of said casing including a base plate having an upstanding flange projecting into and secured to said casing and an annular flange extending radially beyond the casing and provided with a pair of openings arranged diametrically opposite each other, means for closing the upper end of said casing including a ring having a downwardly extending annular flange projecting into and secured to said casing and an annular portion radially extending from said casing and having a pair of openings provided in said extending portion arranged diametrically opposite each other and aligned with the openings of said lower flange, a swinging top plate hinged to said ring and having a downwardly extending annular flange 125

120

125

130

projecting into the interior of said ring and means for securing said top plate to said ring; and a pair of substantially diametrically oppositely arranged suspension elements extending through said openings and secured to the annular flange of said base plate, all as and for the purpose set forth.

2. In diving apparatus of the character described, a hollow cylindrical casing; means for permanently closing the lower end of said casing including a base plate having an upstanding flange projecting into and secured to said casing and an annular flange extending radially beyond the casing and provided with a pair of openings arranged diametrically opposite each other, means for closing the upper end of said casing including a ring having a downwardly extending annular flange projecting into and secured to said casing and an annular portion radially extending from said casing and having a pair of openings provided in said extending portion arranged diametrically opposite each other, a swinging top plate hinged to said ring and having a downwardly extending annular flange projecting into the interior of said ring and means for securing said top plate to said ring; a plurality of reinforcing rings se-

cured to the interior of said casing intermediate its ends, and a pair of substantially diametrically oppositely arranged suspension elements extending through said openings and secured to the annular flange of 35 said base plate, all as and for the purpose set forth.

3. In a diving apparatus of the character described, a casing provided with a side opening, a flexible sleeve secured to said 40 casing near the side opening, a guide sleeve extending through the flexible sleeve, means securing the guide sleeve to the flexible sleeve whereby the guide sleeve is carried by the flexible sleeve, and spring means for 45 resiliently sustaining the flexible sleeve in supporting position.

4. In a diving apparatus of the character described, a casing provided with a side opening, a flexible sleeve having one end 50 secured to the casing near the side opening, a guide sleeve extending through the flexible sleeve, a clamp securing the outer end of the flexible sleeve to the guide sleeve whereby the guide sleeve is supported by 55 the flexible sleeve, and spring means for sustaining said flexible sleeve and supporting said sleeve.

ALEXANDER EBEN CHISHOLM.
